(57) **CLAIM**

The ornamental design for a film sticking device, as shown and described.

DESCRIPTION

FIG. 1 is a front, right and bottom perspective view of a film sticking device, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is an exploded view thereof of FIG. 1.

FIG. 11 is a front, right and bottom perspective view of a second embodiment of a film sticking device.

FIG. 12 is a rear, left and bottom perspective view of the second embodiment of the film sticking device of FIG. 11.

FIG. 13 is a front elevation view of the second embodiment of the film sticking device of FIG. 11.

FIG. 14 is a rear elevation view of the second embodiment of the film sticking device of FIG. 11.

FIG. 15 is a left side elevation view of the second embodiment of the film sticking device of FIG. 11.

FIG. 16 is a right side elevation view of the second embodiment of the film sticking device of FIG. 11.

FIG. 17 is a top plan elevation view of the second embodiment of the film sticking device of FIG. 11.

FIG. 18 is a bottom plan elevation view of the second embodiment of the film sticking device of FIG. 11.

FIG. 19 is a partial enlarged view of an area labeled 19 in FIG. 11; and,

FIG. 20 is an exploded view thereof of FIG. 11.

The broken lines shown in the drawings are included for the purpose of illustrating portions of the film sticking device that form no part of the claimed design.

The dot-dash broken lines depict the boundaries of the enlargements that form no part of the claimed design.
